UNITED STATES PATENT OFFICE.

CHARLES C. SPREEN, OF DETROIT, MICHIGAN, ASSIGNOR, BY MESNE ASSIGNMENTS, TO KELVINATOR CORPORATION, OF DETROIT, MICHIGAN, A CORPORATION OF MICHIGAN.

MECHANICAL REFRIGERATION.

Application filed January 5, 1924. Serial No. 684,637.

To all whom it may concern:

Be it known that I, CHARLES C. SPREEN, a citizen of the United States, residing at Detroit, in the county of Wayne and State 5 of Michigan, have invented a certain new and useful Improvement in Mechanical Refrigeration, of which the following is a full, clear, and exact description, reference being had to the accompanying drawings.

10 My invention relates to mechanical refrigeration. In the drawings accompanying this specification and forming a part thereof I have shown, for purposes of illustration, one embodiment which my invention 15 may assume. In these drawings:

Figure 1 is a section on the line 1—1 of Figure 3,

Figure 2 is a section on the line 2—2 of Figure 1, while

20 Figure 3 is a section on the line 3—3 of Figures 1 and 2.

In the embodiment of my invention herein shown my invention is illustrated as applied to an ice cream cabinet 11 provided with a 25 bottom wall 12, a front wall 13, a rear wall 14, an end wall 15, and a partition wall 16 dividing the cabinet into a refrigerating compartment (not shown) and a compressor compartment, and positioned within the 30 cabinet 11 on the compressor chamber side of the partition 16 is a compressor unit 31 comprising a compressor 32 having its inlet 33 connected by means of a duct 34 to the outlet 35 of an expansion coil located within 35 the refrigerating chamber, a condensing coil 36 having its inlet 37 connected through a shut-off valve 38 to the outlet 39 of the compressor 32, an expansion valve 40 having its inlet connected through a shut-off valve 41 40 to the outlet end 42 of the condensing coil 36 and its outlet connected through a duct 43 to the inlet end of the expansion coil, and an electric motor 45 arranged to operate the compressor 32 by means of a belt 46.

45 The condensing coil 36 is herein shown as surrounded by a casing 47 provided near its upper end with an opening 48 for the outlet of the cooling air circulating about the condensing coil 36 and near its lower

end with an opening 49 for the inlet of this 50 circulating air. The opening 49 is positioned directly in front of a fan 50 carried by the shaft 51 of the motor 45 and is elongated to remain in front of the fan 50 during the travel of the motor 45 in response 55 to means connected to the motor 45 to constantly urge the motor 45 away from the compressor 32 to thus maintain tight the belt 46 connecting the motor 45 and the compressor 32. To facilitate the passage of the 60 circulating air into and out of the casing 11 the casing 11 is provided with two sets of louvres 52 and 53 positioned respectively adjacent the outlet opening 48 in the condenser coil casing 47 and the fan 50 and 65 inlet opening 49 of the condenser casing 47. If desired the fan 50 may be surrounded by a perforated housing 54 provided with a plurality of air inlet openings 55 and an elongated opening 56 for the passage of the 70 shaft 51 during the transverse movement thereof.

It will be readily apparent to those skilled in the art that the particular embodiment of my invention herein disclosed may be readily 75 changed and modified without departing from the spirit of my invention or sacrificing the advantages thereof and it will therefore be understood that the disclosure herein is illustrative only and my invention 80 not limited thereto.

I claim:

1. In combination, a compressor unit comprising a compressor and a motor for operating said compressor mounted for movement transverse to the axis of said motor to maintain tight the belt connecting said motor and said compressor, a fan carried by said motor, an air cooled condensing coil connected to the outlet of said compressor, and an enclosure surrounding said coil and provided with at least one inlet opening and at least one outlet opening and having one of said openings arranged to cooperate with said fan and elongated to register with said fan during the transverse movement of said fan.

2. In combination, a compressor unit com-

- prising a compressor and a motor for operating said compressor mounted for movement transverse to the axis of said motor to maintain tight the belt connecting said motor and said compressor, a fan carried by said motor, an air cooled condensing coil connected to the outlet of said compressor, an enclosure surrounding said coil and provided with at least one inlet opening and at least one outlet opening and having one of said openings arranged to cooperate with said fan and elongated to register with said fan during the transverse movement of said fan, and a cabinet enclosing said compressor unit and said enclosure and said fan and provided with an inlet opening arranged to cooperate with an inlet opening of said enclosure and an outlet opening arranged to cooperate with an outlet opening of said enclosure, one of the openings in said casing cooperating with the enclosure opening which cooperates with said fan.

3. In combination, a compressor unit comprising a motor part and a compressor part, and an air cooled condensing coil connected to the outlet of the compressor, an enclosure surrounding said coil and provided with at least one inlet opening and at least one outlet opening, a fan positioned at one of said openings and arranged to circulate air about said coil, and a cabinet enclosing said compressor unit and said enclosure and said fan and provided with an inlet opening arranged to cooperate with an inlet opening of said enclosure and an outlet opening arranged to cooperate with an outlet opening of said enclosure, one of the openings of said cabinet cooperating with the enclosure opening which cooperates with said fan.

4. In combination, a compressor unit, an air cooled condensing coil connected to the outlet of the compressor, an enclosure surrounding said coil and provided with at least one inlet opening and at least one outlet opening, and a cabinet enclosing said compressor unit and said enclosure and provided with an inlet opening arranged to cooperate with an inlet opening of said enclosure and an outlet opening arranged to cooperate with an outlet opening of said enclosure.

5. In combination, a fan, a belt connecting said fan with another machine, a mounting for said fan arranged to move said fan transversely of the axis of said fan to maintain said belt tight, an air cooled condensing coil, and an enclosure surrounding said coil and provided with an opening cooperating with said fan and elongated to register with said fan during the transverse movement of said fan.

6. In combination, a fan, a belt connecting said fan with another machine, a mounting for said fan arranged to move said fan transversely of the axis of said fan, an air cooled condensing coil, and an enclosure surrounding said coil and provided with an opening cooperating with said fan and elongated to register with said fan during the transverse movement of said fan.

7. In combination, a compressor unit having one part mounted for movement transverse to the axis of said part, a fan carried by said part, an air cooled condensing coil connected to the outlet of the compressor, an enclosure surrounding said coil and provided with at least one inlet opening and at least one outlet opening and having one of said openings arranged to cooperate with said fan and elongated to register with said fan during the transverse movement of said fan.

8. In combination, a compressor unit comprising a motor part and a compressor part, and having one part mounted for movement transverse to the axis of said part, a fan carried by said part, an air cooled condensing coil connected to the outlet of the compressor, and an enclosure surrounding said coil and provided with at least one inlet opening and at least one outlet opening and having one of said openings arranged to cooperate with said fan and elongated to register with said fan during the transverse movement of said fan.

9. In combination, a compressor unit comprising a motor part and a compressor part, and having one part mounted for movement transverse to the axis of said part to maintain tight the belt connecting said part with another portion of said unit, a fan carried by said movable part, an air cooled condensing coil connected to the outlet of the compressor, and an enclosure surrounding said coil and provided with at least one inlet opening and at least one outlet opening and having one of said openings arranged to cooperate with said fan and elongated to register with said fan during the transverse movement of said fan.

10. In combination, a compressor unit comprising a motor part and a compressor part, and having one part mounted for movement transverse to the axis of said part to maintain tight the belt connecting said part with another portion of said unit, a fan carried by said movable part, an air cooled condensing coil connected to the outlet of the compressor, an enclosure surrounding said coil and provided with at least one inlet opening and at least one outlet opening and having one of said openings arranged to cooperate with said fan and elongated to register with said fan during the transverse movement of said fan.

cooperate with said fan and elongated to register with said fan during the transverse movement of said fan, and a cabinet enclosing said movable part and said enclosure and said fan and provided with an inlet opening arranged to cooperate with an inlet opening of said enclosure and an outlet opening ar- ranged to cooperate with an outlet opening of said enclosure, one of the openings in said casing cooperating with the enclosure 10 opening which cooperates with said fan.

In testimony whereof, I hereunto affix my signature.

CHARLES C. SPREEN.
